UNITED STATES PATENT OFFICE.

CARL E. KLAMM, OF CLEVELAND, OHIO.

FIXTURE FOR WINDOW-SHADES.

1,172,715.

Specification of Letters Patent   Patented Feb. 22, 1916.

Application filed May 8, 1915. Serial No. 26,704.

To all whom it may concern:

Be it known that I, CARL E. KLAMM, a citizen of the United States, residing at Cleveland, in the county of Cuyahoga and State of Ohio, have invented certain new and useful Improvements in Fixtures for Window-Shades, of which the following is a specification.

This invention relates to fixtures for window shades, the object being to provide a shade hanger or device for supporting a shade roller, the hanger being adjustable so that it may be raised or lowered to support the shade roller in any desired position on the window casing.

The invention will be found particularly useful for purposes of ventilation, as the shade can be lowered from the top, by lowering the hanger, and by opening the upper window sash a free circulation of air is permitted.

Improved means are provided for holding the hanger in its various adjusted positions.

In the accompanying drawings—Figure 1 is a front elevation of a window provided with the device. Fig. 2 is a vertical section, showing the hanger secured to the inner edge or side of the casing. Fig. 3 is a detail of the latch for holding the hanger at adjustment. Fig. 4 is an inside elevation showing the adjusting devices. Fig. 5 is a sectional elevation of the same. Fig. 6 is a top view of the parts shown in Fig. 4.

In the drawings, 6 indicates the window casing and 7 the sash.

8 is a shade roller. This is supported at its ends by brackets 9, each of which is mounted on a slide 10 and projects through a slot 11 in a housing 12 which is secured to the inner face of the window casing. The slide 10 has inclined side flanges which engage the inclined or undercut surfaces 13 behind the slot 11 in the housing 12, to hold the slide in proper position, the head of the bracket 9 projecting beyond orlapping the edges of the slot on the outside of the casing, whereby the slide and bracket are held against lateral movement, but are free to move up and down for adjustment. Such

adjustment is effected by a rod 14 which is connected at its upper end to the slide 10, by a pivot pin 15, and is provided at its lower end with an operating knob 16, the connecting stem 17 of which extends through a slot 18 in the lower part of the housing 12. The rod also has, at its lower end, a cross piece 19 which bridges the slot 18 and is adapted to engage a pair of fingers 20 which are struck up from metal strips 21 secured to the inner recessed face of the housing 12, and extending vertically beside the slot 18. A series of fingers 20 are provided at different vertical positions, to hold the hanger at various elevations as desired. A flat spring 22 is fixed to the back of the cross piece 19 and bears against a wear strip 23, behind the casing 12, and this spring normally holds the catch 19 in engagement with the fingers 20.

In operation the rod 14 may be raised or lowered by means of the knob 16, the catch 19 being disengaged by pressing in on the knob, and the slide 10 will be accordingly raised or lowered to set the shade roller in desired position. In Fig. 1 it is shown dropped some distance from the top of the casing, to permit ventilation at the top. In operation both knobs 16 will be grasped and adjusted simultaneously.

What I claim as new is:

A shade hanger comprising a slotted housing, strips attached to the inside of the housing beside the slot, said strips having tongues struck up therefrom, a slide in the upper part of the housing, having a bracket projecting through the slot and flanges engaging the outer side of the housing beside the slot, a depending rod pivoted at its upper end to the slide and having a beveled cross piece at its lower end engageable with said tongues, and a finger piece projecting from said cross piece and through the slot.

In testimony whereof, I affix my signature in presence of two witnesses.

CARL E. KLAMM.
